UNITED STATES PATENT OFFICE.

JAMES TURNER AND PEARL P. CRABILL, OF SPRINGFIELD, OHIO.

BUMPER FOR AUTOMOBILES.

Application filed January 10, 1923. Serial No. 611,712.

To all whom it may concern:

Be it known that we, JAMES TURNER and PEARL P. CRABILL, citizens of the United States, residing at Springfield, in the county 5 of Clark and State of Ohio, have invented certain new and useful Improvements in Bumpers for Automobiles, of which the following is a specification.

Our invention relates to improvements in 10 bumpers for automobiles.

One of the objects of our invention is to provide an improved construction of double rail; a more specific object in this connection being to provide a novel means for connecting the rails together and spacing same 15 apart.

A further object of our invention is to provide a simple and effective arrangement for supporting the bumper rails from the 20 vehicle; a more specific object in this connection being to provide an improved form of bracket capable of being connected to both the frame and spring bolt and so arranged that it can be adjusted to support the bumper 25 rails in the proper horizontal position, and also adjusted to avoid such parts as rivets and bolts in the frame members and also to accommodate itself to snubbers, shock absorbers, splash pans or other appliances 30 which are attached to the frame members.

Referring to the drawings:

Fig. 1 is a top plan view of the forward end of a motor vehicle showing our improved bumper applied thereto.

Fig. 2 is a front view of the bumper.

Fig. 3 is a top plan view of a portion of the bumper showing a modification.

Fig. 4 is also a top plan of a portion of the bumper showing a further modification.

Fig. 5 is a section on the line 5-5 of Fig. 9.

Fig. 6 is a section on the line 6-6 of Fig. 2.

Fig. 7 is a section on the line 7-7 of Fig. 3.

Fig. 8 is an enlarged top plan view of one of the supporting brackets.

Fig. 9 is a side elevation of the supporting bracket with the member to which it is 50 attached at its forward end shown in section.

Fig. 10 is a perspective view showing a modified form of supporting bracket.

Referring to the drawings, 1 and 2 represent a pair of bumper rails or bars formed 55 of flat spring metal arranged in vertical

alignment with each other and also in spaced-apart relation. The free ends of these bars are curved slightly rearwardly and are each formed with an eye 3, adjacent eyes being 60 adapted to receive a bolt 4 by which the rails are firmly connected together; spacing sleeves 5 being placed about the bolts between adjacent eyes 3 so as to hold the rails 1 and 2 in proper spaced relation (see 65 Fig. 7 for detail).

The rails 1 and 2 are connected to an intermediate member 6 formed of flat spring metal having its ends curved, with the extreme portions 6' thereof extending in parallel relation with the main portion 6. The bars 1 and 2 are connected with the portions 6' of the intermediate member by a pair of clamps. Each of these clamps, as shown in Fig. 6, is formed of two members, a forward 70 member 7 and a rear member 8. The forward member has top and bottom flanges 9 and a central horizontal rib 10 which cooperates with the flanges to form top and bottom channels which receive the rails 1 and 2, while the rear clamping member is formed with a horizontal channel 11 which receives the parts 6' of the intermediate member. A bolt 12 secures the two clamping members 75 together.

In Figs. 3 and 4 a modification is shown in the form of the intermediate supporting member in which case this member is formed of two separate parts 6'', each part having its end curved and connected to the rails 1 and 2 exactly in the same manner as described.

The bumper thus formed is connected with the vehicle frame by a pair of bracket members. Each of these bracket members 95 is constructed as follows: A horizontal portion 13 has at one end a short rearwardly and downwardly extending arm 14 and at the other end a short rearwardly projecting arm 15 to which is connected a separate arm 100 16, the forward and rear parts of which are laterally offset as shown. The horizontal portion 13 is secured to the intermediate member 6 by a U-shaped clamp 17 having its free ends drawn together by bolts 18. The rear end of the arm 14 is connected to the frame through the medium of the spring bolt 19. The arm 16 is adjustably connected to the arm 15 by the bolt 20, the arm 16 being provided with a pair of orifices 21 each 105 adapted to receive this bolt so that the attachment consisting of the two arms 15 and 110

16 may be shortened or lengthened as desired. The rear end of the arm 16 is connected to the channel frame member 22 by a bolt 23 having a hook-shaped flattened end 5 24 which engages the lower flange of the frame member 22 and a wedge member 25 loosely sleeved on the bolt to engage the under surface of the lower flange of the frame and also the outer surface of the central 10 vertical web thereof, the member 25 having a vertical bifurcated integral flange 26 for this latter purpose. The rear end of the arm 16 is clamped against the member 25 and its flange 26 by the nut 27, a spacing washer 28 and a spring lock washer 29 being preferably inserted between the nut and arm.

In Fig. 10 there is shown a modification. In this case the horizontal portion indicated 20 at 13' terminates substantially flush with the inner end of the clip, indicated at 17', and is provided with but a single rearwardly projecting arm 14' which corresponds to the arm 14 previously described. The clip 25 17' is formed with an integral rearwardly-extending ear 30 perforated to receive the bolt 20 which connects thereto an arm, shown in dotted lines at 16', which corresponds to the arm 16 previously described.

30 By this arrangement of bracket it will be seen that the parts may be adjusted relatively to each other so as to permit the bumper rails to be raised or lowered to bring them in proper position relatively to the wheel base of the vehicle and the arm 16 may also be adjustably attached to the arm 15 or ear 30, as the case may be, to permit the avoidance of rivets, bolts, snubbers, shock absorbers, splash pans or other parts by enabling 40 the clamping bolt 23 and its wedge 25 to be applied to the frame at different points in its length and to also enable the arm 16 to be attached to the arm 15 either in the manner shown in Fig. 1, or in the manner shown 45 in Fig. 3 or Fig. 4.

Having thus described our invention, we claim:

1. In a bumper, a pair of spaced-apart impact rails arranged in parallel relation and

vertical alignment throughout their length, 50 means for connecting adjacent ends of said rails together, an intermediate rail having its ends bent forwardly with the extreme portions thereof arranged parallel with said impact rails at points removed from their ends and connected therewith, and means for supporting said intermediate rail from a motor vehicle.

2. In a bumper, a pair of front spaced-apart impact rails arranged in parallel relation and vertical alignment throughout their length, means for securing adjacent ends of said rails together, a bracket member secured to each side of a motor vehicle, and intermediate connecting means secured 65 to said brackets, said connecting means being bent forwardly and having the bent portions thereof arranged parallel with and clamped to said impact rails at points removed from their ends. 70

3. In a bumper, a pair of resilient spaced-apart impact bars arranged in parallel relation and vertical alignment throughout their length, means for spacing apart and rigidly connecting their extreme adjacent 75 ends, an intermediate member having bent ends lying parallel with the rear side of said impact bars at points removed from their ends, and clamps for securing said bent ends to said impact bars. 80

4. In an automobile bumper, a bumper member, a bracket for securing said bumper member to the vehicle comprising a clamping member and a pair of arms, one projecting rearwardly at each end of the clamping member, one of said arms being arranged to be clamped to the spring bolt, and a bar connected to the other of said arms, together with means for clamping said bar to the vehicle frame, said bar and its companion arm being arranged to be fastened together at different points in the length of said bar to permit said bar to be clamped to said frame at different points. 90

In testimony whereof, we have hereunto set our hands this 5th day of January, 1923.

JAMES TURNER.
PEARL P. CRABILL.
